FAN

Theodore A. Fulton, Seattle, Wash., assignor to Flex-A-Lite Corporation, Tacoma, Wash.

Filed Apr. 29, 1974, Ser. No. 465,115

Term of patent 14 years

Int. Cl. D23—04

U.S. Cl. D23—165

FIG. 1

FIG. 2

FIG. 3

FIG. 4

FIG. 1 is a front elevation of a fan;
FIG. 2 is a rear elevation of the fan;

FIG. 3 is a side view looking at the end of one blade of the fan; and

FIG. 4 is a side view looking at the fan and between two adjacent blades and which fan has been rotated thirty (30°) degrees with respect to the view of FIG. 3.

I claim:

The ornamental design for a fan, substantially as shown.
